STACK SWITCH

Lawrence M. Persons, St. Louis County, Mo., assignor to Automatic Control Corporation, St. Louis, Mo., a corporation of Delaware

Application April 24, 1939, Serial No. 269,634

4 Claims. (Cl. 200—122)

The present invention relates to stack switches and, in particular, to thermostats having heat-responsive units within some space, such as the stack, that is immediately responsive to any changes in heat conditions of a furnace and which thermostat operates a switch upon any change of the heat device within such critical space.

In particular, the stack switch is adapted to be connected in series with a room thermostat.

Objects of the invention include the provision of such a switch having an influencing unit displaceable in response to some external condition from position wherein it influences a control unit to a position wherein it does not influence the unit; and, specifically, the provision of a stack thermostat moving a heating unit toward or from a heat-responsive element so that the operation of the heat-responsive element is made dependent upon the position of the heating unit and hence upon the temperature condition of the stack.

A further object of the invention is the provision of compensated thermal elements controlling the main switch, both to eliminate deleterious effects of ambient temperatures and to enable a heat-producing unit to be employed to influence the thermal elements for operation of the main switch, which heat-producing unit need not be deenergized during cycling of the mechanism.

In the drawings:

Fig. 1 is a plan view of the mechanism with the thermal unit broken away;

Fig. 2 is a front elevation;

Fig. 3 is a side elevation taken from the right of Figs. 1 and 2;

Fig. 4 is a horizontal section taken on the line 4—4 of Fig. 2;

Fig. 5 is a horizontal section taken on the line 5—5 of Fig. 2;

Fig. 6 is a vertical section taken on the line 6—6 of Fig. 2;

Fig. 7 is a vertical section taken on the line 7—7 of Fig. 2 and is similar to the top part of Fig. 6 but looking in the other direction;

Fig. 8 is a horizontal section taken on the line 8—8 of Fig. 2;

Fig. 9 is a vertical section taken on the line 9—9 of Figs. 1 and 2;

Fig. 10 is a vertical section taken on the line 10—10 of Fig. 1;

Fig. 11 is a horizontal section taken on the line 11—11 of Fig. 10; and,

Fig. 12 is a wiring diagram of the mechanism.

The mechanism includes a box portion 15 from the back of which there extends a supporting tube 16 rigidly attached to the box. At the outer end of the tube 16 is attached one end of a helical bimetal 17, the outer end of which is fixed to a driving shaft 18 that passes axially through the helix, the tube, and the box, and having a reduced portion 19, projecting from the front wall 20 of the box.

10 Through the wall 20 and about the rod 18 is a sleeve 21, the flange of which extends flush with the shoulder marking the beginning of the reduced portion 19 of the rod 18.

Against this shoulder and over the reduced portion 19, there is disposed a friction disc 22 having integrally formed therewith a sleeve portion 23 that extends toward the end of the portion 19. Over the sleeve 23 and against the disc 22 is the upper end 24 of a heater-carrying arm, outside of which is a second friction disc 25 also disposed over the sleeve 23. An S-shaped leaf spring 26 fits over the sleeve 23, bears against the disc 25 and is held in place by a collar 27. A pin 28 passes through the collar 27, the sleeve 23 and the portion 19 of the shaft 18. It thus may be seen that a friction clutch is provided causing the member 24 normally to rotate with the shaft 18 but movable relative thereto against the friction of the two discs 22 and 25 produced by the spring 26.

30 The member 24 has a depending arm 30 thereon that projects downwardly therefrom. It has a slot 31 over a pin 32, the pin being secured to the front plate 20, and thereby limiting movement of the arm 30.

A heater-carrying plate 35 is attached to one edge of the arm 30, there being feet 36 and 37 turned at 90° from the blade 35 and secured by screws 38 and 39 to the arm 30. A low resistance heater coil 40 is wrapped around the blade 35 and the terminals of this heater coil are secured respectively to the screws 38 and 39. Flexible leads 42 and 43 extend from the screws 38 and 39 through slots 44 and 45 in the plate 20. The arcuate shape of the slots accommodates movement of the leads with the arm 30.

An additional arm 48 extends outwardly from the upper part of the member 24 in position to actuate a switch 49 by forcing a spring blade 50 into contact with the spring blade 51. The normal springing of these blades causes the switch to open.

The depending arm 30 with its heater 40 is oscillated by the helical bimetal 17 between two oppositely acting and mutually compensating bi-

metal strips 54 and 55 secured to a pivot block 56. The block is attached to a pivot 57, that in turn is secured to the front plate 20. A spacing collar 58 is provided about the pivot 57.

One end of the bimetal 54 is slotted at 59 to receive a point 60 projecting from the shoulder on an adjustable screw 61 threaded through an angle bracket 62 attached to the front plate 20. A lock nut 63 holds the screw 61 in adjusted position. The slot 59 permits displacement of the bimetal as it pivots about the pivot 57, as is shown in Fig. 7.

The bimetal 55 controls a switch generally indicated at 65. This switch has two blades 66 and 67 that may be brought into contact with each other. The blade 67 is secured to a block 68 on the front plate 20 and has a terminal member 69 extending through the plate 20, to which is attached a lead 70.

An insulating block 71 passes over the blade 67. The blade 66 is located on the opposite side of the insulating block 71 and it has a terminal member 72 extending through the front plate 20. The other end of lead 43 is attached thereto. An additional insulating block 74 passes outside the blade 66. Screws 75 and 76 extend through the several blocks and blades as well as the front plate 20 to hold this switch thereto.

The two spring switch blades 66 and 67 are normally inherently urged apart to separate their contact elements. The top blade 66 has a projection 80 extending laterally from the outer end thereof to engage beneath a notch 81 in the bimetal 55. When normally engaged beneath the notch, the blade 66 is held down in contact with the blade 67, as in Fig. 9. When the bimetal pivots away from the projection 80, the inherent resiliency of the blade 66 moves it away from the blade 67, thereby opening the switch.

A reclosing button 83 has a reduced portion 84 passing through an opening 85 in the blade 66 and the slot 86 in the blade 67. This arrangement provides a shoulder on one side of the blade 66 and a shoulder on the other side of the blade 67, the first of these shoulders providing means for reengaging the blade 66 beneath the notch 81 on the bimetal 55 and the other shoulder preventing withdrawal of the button.

An angular cover plate 89 projects over the switch 65 to protect the same and has an opening 90 through which the button 83 projects.

As shown in Fig. 11, the switch blades 50 and 51 of the smaller switch 49 project through the front plate 20 and have leads 92 and 93 extending therefrom.

There are six terminals on the plate 20. The terminals 95 and 96 are connected across the power lines 97 and 98. The terminals 99 and 100 are connected externally with the leads 101 and 102 to the burner ignition means BI, or the valve or other proper mechanism controlling the furnace. The terminals 103 and 104 are connected by the leads 105 and 106 to the room thermostat T.

Referring to Fig. 12, the internal connections may be seen. A primary 108 of a transformer (located within the box 15) is connected directly across the terminals 95 and 96 by leads 109 and 110. The terminals 96 and 99 are connected in series by a lead 111. The terminal 95 is connected in series with the terminal 100 by a lead 112 that passes through one side 113 of a relay 114 and thence by a lead 115 to the terminal 100.

The secondary 116 of the transformer has a lead 117 passing through the coil 118 of the relay 75

114 and thence by a lead 119 to the terminal 104, whence the coil is put in series with the room thermostat T. From the terminal 103 there extends a lead 120 to a junction 121. One lead 122 from this junction leads through the other side 123 of the relay and thence by line 124 to a junction 125. From this junction 125 extends the flexible lead 42 attached to one end of the heater 40. The other end of the heater 40 by lead 43 extends to switch blade 66 connected with the switch blade 67, which, by lead 70, is connected to the return end of the primary 116.

From the junction 125, the lead 82 leads to the blade 60 of the switch 49 and through the other blade 51 and the lead 93 to the junction 121.

Operation

The operation of the device is as follows:

It is assumed that if the connections are made as above indicated, the primary 108 of the transformer will be connected directly across the line. The burner control or igniter BI will be out of circuit because the relay 114 is open at 113. It will also be assumed that the room thermostat is open. The stack temperature will be low, hence the coil 17 cold so that the rod 18 and with it the arm 30 are rotated through a maximum distance in a counterclockwise direction, viewed in Figs. 2 and 12. In this position, the heater 40 is disposed adjacent the bimetal 55. Likewise the switch 49 is closed through the action of the arm 48 in its most counterclockwise position. The switch 65 is closed by engagement with the bimetal 55.

The first change will occur in the event the room thermostat closes, demanding heat. In this case, current will flow from the secondary 116 through the line 117, the coil 118, the line 119, the terminal 104, the line 106, the thermostat T, the line 105, the terminal 103, the line 120, the junction 121, the line 93, the switch 49, the line 92, the junction 125, the line 42, the heater 40, the line 43, the switch 65 and the line 70 to the opposite end of the secondary. This causes the heater to be energized and also closes the relays 113 and 123. When the relay 113 is closed, the igniter BI is put across the line as follows: line 97, terminal 95, line 109, line 112, relay 113, line 115, terminal 100, line 102, the igniter, line 101, terminal 99, line 111, terminal 96, and line 98. The furnace will then start supplying heat both to the stack, almost instantly, and more slowly to the room wherein the thermostat T is located.

As the stack heats, the helical bimetal 17 turns the shaft 18 in a clockwise direction, withdrawing the heater from its position in proximity to the bimetal 55 to a middle position between the two bimetals 55 and 54, in which position the bimetals act oppositely and preserve the status of the switch 65. If the helix 17 deflects more than the degree of rotation permitted by the slot 31, the slip clutch admits of relative movement between the shaft 18 and the arm 30.

In normal cycling, the furnace will ultimately warm the thermostat T, which then will open. This deenergizes the heater and the relay 114, and by the latter, the igniter BI. The stack will cool in due course, bringing the arm 30 and heater 40 to starting position near the bimetal 55. Since the movement of the helix 17 between the maximum and minimum of normal operation is much greater than the permitted movement of the arm 30, that arm is in starting posi-

tion very early in the cooling stage of the stack, and in its operating position between the bimets very early in the heating stage of the stack. Thus proper cycling may be initiated in both directions from practically any stack temperature.

It is evident that the switch 49 is opened when the stack has heated causing displacement of the arms 30 and 48. If the stack is hot, such as caused by periodic operation of the furnace, but the effect of the operation has not yet reached the room thermostat, closing of the thermostat will produce no effect until the stack cools, because the circuit is open at both the switch 49 and the relay 113. The furnace cannot be over-loaded.

If, when the room thermostat first closes, the stack does not heat, owing to a failure of ignition or the like, the arm 30 and the heater 40 will not be displaced. The time required for the heater to heat and act upon the bimets is no less than the time normally required for the helix 17 to be heated to remove the heater from the bimetal 55. But where the arm 30 remains near the bimetal 55 for an undue interval produced by failure of the stack to heat, the bimetal will move away from the blade 66 and permit the two blades 66 and 67 to spring apart. Since the switch 65 controls the entire secondary circuit, that circuit will be deenergized, and relay 114 will open at both 113 and 123. The furnace will thereby be completely cut off if the stack fails initially to heat.

If the stack does heat, and having attained a certain temperature, improperly cools for any reason, the helix 17 will deflect the heater toward the bimetal 55, and in due time cause this bimetal to release the switch 65, opening the circuits. It is immaterial what the stack temperature is from which the drop begins, since the slip clutch action causes displacement of the heater upon any reduction in temperature of an amount sufficient to displace the arm 30 toward the bimetal 55. The device thus operates upon change of temperature.

Whenever the switch 65 is opened, it may be closed again only by depressing the button 83. It will remain closed only if the bimetal 55 is at a normal temperature relative to that of the bimetal 54.

What is claimed is:

1. In a mechanism of the kind described, a pair of spaced and oppositely acting bimets joined for pivotal movement together about a given point, said bimets extending from such pivot point, an adjustable abutment for the free end of one bimetal, an actuated mechanism controlled by the free end of the other bimetal, a heater, and means supporting the heater between the bimets and movable toward one or the other thereof.
2. In a mechanism of the kind described, a base, a shaft thereon, means to displace the same about its axis, an arm on the shaft, a heater on the arm and pivotable therewith, a pair of oppositely acting thermal devices, means securing them together at one end and mounting them for pivotal movement on the base, means holding the free end of one means actuated by the free end of the other, the thermal devices being disposed one on each side of the heater, and the heater being movable toward one or the other thermal device.
3. In a mechanism of the kind described, a base, a shaft thereon, means to displace the same about its axis, an arm on the shaft, a heater on the arm and pivotable therewith, a pair of oppositely acting thermal devices, means securing them together at one end and mounting them for pivotal movement on the base, means holding the free end of one means actuated by the free end of the other, the thermal devices being disposed one on each side of the heater, and the heater being movable toward one or the other thermal device, a switch, and means on the arm to actuate the switch upon displacement of the arm.
4. In a mechanism of the kind described, a base, a shaft thereon, means to displace the shaft about its axis, an arm on the shaft, a heater on the arm and pivotable therewith, a pair of oppositely operating bimetallic strips, means connecting the strips together at one end and securing them pivotally to the base, means adjustably holding the free end of one strip against displacement, and means actuated by the free end of the other strip.
